(57) **CLAIM**

The ornamental design for a combined bottle and cap, as shown and described.

DESCRIPTION

FIG. 1 is a top, front perspective view of a combined bottle and cap, showing our new design;

FIG. 2 is a front elevational view thereof;

FIG. 3 is a rear elevational view thereof;

FIG. 4 is a right side elevational view thereof;

FIG. 5 is a left side elevational view thereof

FIG. 6 a top plan view thereof; and,

FIG. 7 is a bottom plan view.

The dashed broken lines depict features of the combined bottle and cap that form no part of the claimed design.

1 Claim, 4 Drawing Sheets
